UNITED STATES PATENT OFFICE.

WARREN F. FRASER, OF BOSTON, MASSACHUSETTS.

CLEAT.

1,231,725.

Specification of Letters Patent. Patented July 3, 1917.

Application filed September 1, 1914. Serial No. 859,627.

To all whom it may concern:

Be it known that I, WARREN F. FRASER, a subject of King George V of England, residing at Boston, in the county of Suffolk 5 and State of Massachusetts, have invented new and useful Improvements in Cleats, of which the following is a specification.

This invention relates to improvements in cleats and more particularly, though not 10 exclusively, to cleats adapted for use in tanning or curing hides. When used in this connection the cleats are secured upon a frame and a series of cords, commonly known in the art as toggles, are secured at 15 intervals along the edges of the hides with their free ends attached to said cleats, thus stretching said hides taut within the frame.

There are at the present time cleats in use for this purpose, but in securing the 20 cords of the toggle to such the ends of said cords must be kept tight as they are secured thereto by means of what is known as the "black-wall or painter's hitch," the principle of which is to bend a cord about the 25 shank of the cleat laying the free end of the cord beneath its taut end which prevents the slipping thereof.

There is a decided objection to this type 30 of fastening means for the reason that should the cord extending from the cleat to the hide become slackened, which it invariably does when the hides are being stretched, the end of the same will become detached from the cleat.

The object of this invention is to provide 35 a simple inexpensive and durable cleat which is adapted to be conveniently attached to the frame within which the hides are tanned or cured, said cleat having provision 40 for securing the free end of the cord in such a manner that as the tension on said cord is increased said end will be more firmly bound and secured thereon, while at the same time said end will be firmly held 45 should the cord be at any time slackened or the tension thereon released.

The invention consists in the combination and arrangement of parts whereby the above object and certain other objects hereinafter appearing may be attained, as set forth in the following specification and particularly pointed out in the claims.

Referring to the drawings:

Figure 1 is a plan view of a cleat embodying my invention attached to a portion of a frame.

Fig. 2 is a side elevation of the cleat illustrated in Fig. 1 with the frame to which the same is attached shown in section.

Fig. 3 is a plan view of a modified form 60 of cleat illustrating another method of securing said cleat to said frame.

Fig. 4 is a plan view of still another form of cleat.

Like numerals refer to like parts throughout the several views of the drawings.

In the drawings, referring to Figs. 1 and 2, 5 is a portion of a frame preferably constructed in the usual manner and 6 a cleat to which is secured a cord 7 constituting 70 the end of what is usually known to those skilled in the art as a toggle. The cleat 6 is preferably constructed of wire and from a single piece of wire which is bent at suitable points to form a shank portion 8, 75 a transversely disposed member 9, which in other words constitutes a pair of hooks, a resilient member or tongue 10, and means for securing the cleat 6 to the frame 5, which in the present instance are prongs 11 80 adapted to be driven into the wood of said frame within a depression 12 provided in the face of the frame 5 in order that the cleats may be retained between the upper and lower faces 13 and 14 respectively of 85 said frame.

To form the cleat illustrated in Figs. 1 and 2 the wire from which the same is constructed is bent double or looped at 15 to form the tongue 10. At a substantial distance from the loop 15 the legs of the wire are bent outwardly at 16 substantially in opposite directions to form the transverse member or hooks 9, said legs being again bent at 17 returning parallel with portions 95 9 to the points 16, following the lines of said bends 16 and thence extending substantially parallel with the tongue 10 to form the shank 8. At points 18, which are adjacent the loop 15, the ends of said wire are 100 preferably bent outwardly or divergently to points 19 one of which is preferably at a greater distance from the loop 15 than the other. At 19 the wires are then bent substantially at right angles to the shank 8 to 105 form prongs 11, the ends thereof being preferably sharpened to permit the same to be easily driven into the frame 5, said prongs being arranged out of alignment with each other in order to prevent the cracking of 110 said frame when said prongs are driven into the same. The extremity of the tongue 10

adjacent the loop 15 is bent outwardly to facilitate the insertion of the cord 7 between said tongue and the shank 8 of said cleat. In securing the cord 7 to the cleat, 5 the end 20 thereof is drawn taut in the direction of the arrow "a" and bent around the shank portion 8 and the tongue 10 between the taut portion 21 thereof and the hook against which said cord is resting, 10 which in the present case, is "b" after which said end 20 is laid between the tongue 10 and the shank 8, said tongue and said shank being sufficiently close together to firmly grip said end and prevent the withdrawal thereof in case the tension on the 15 portion 21 of said cord is relaxed.

It will be evident in view of this arrangement that the cord will be gripped at two points, the first point being at "c" at which 20 point said cord is pinched between the taut end 21 thereof and the hook "b" and constituting what is generally known as a "black-wall or painter's hitch." The other point at which said cord is gripped is at "d" between 25 the tongue 10 and the shank 8, the grip of said members being increased by the tension on the cord 21, due to the fact that the end of said cord is coiled around both said tongue and said shank and the more the 30 tension on the end 21 of said cord is increased the greater will be the gripping pressure between said members.

In Fig. 3 I have shown a cleat 6' similar in every respect to the cleat 6 with the exception of the ends 22 of the wires forming the shank 8', said ends being formed into eyes 23 instead of prongs as at 11, said eyes being arranged to receive tacks or the like 24 by means of which said cleat may be attached 40 to the frame 5'.

In Fig. 4 I have shown still another form of cleat differing from the others by reason of its being constructed of sheet metal rather than from wire. The cleat in this form consists of a shank 25, transverse member or hooks 26, tongue 27 and eyes 28 by means of which said cleat may be secured to a hide stretching frame, the arrangements of said several members being substantially identical 45 with those illustrated in Figs. 1, 2 and 3 and adapted to receive the cord in a like manner. The tongue 27 in this form of cleat is formed by partially detaching portions of the material constituting said cleat 50 from the shank 25, said shank being bent outwardly to provide a space between said tongue and said shank through which said cord may be drawn.

While I have herein shown and described 60 one specific embodiment of my invention for illustrative purposes, and have disclosed and discussed in detail the construction and ar-

rangement incidental to the specific applications thereof, it is to be understood that the invention is limited neither to the mere 65 details or relative arrangement of parts, nor to its specific application herein shown, but that extensive deviations from the illustrated forms or embodiments of the invention may be made without departing from 70 the principles thereof.

Having thus described my invention what I claim and desire by Letters Patent to secure is:

1. A cleat formed from a single piece of 75 wire bent double to form a tongue, the ends of said wire forming said tongue being then bent outwardly at the base of said tongue in substantially opposite directions substantial 80 distances from said tongue, thence doubled 85 inwardly close to said outwardly extending portions to form hooks, the ends of said wire forming said hooks being thence bent into parallel sections extending from the base of said tongue longitudinally thereof and substantially parallel therewith to form a shank, the ends of the wires forming said shank being thence bent divergently relatively to each other substantially in a plane containing the longitudinal median lines of 90 wires forming said shank, the ends of said divergently extending portions being bent at right angles to said plane to form prongs adapted to secure said cleat to a support.

2. A cleat formed from a single piece of 95 wire bent double to form a tongue, the ends of said wire forming said tongue being then bent outwardly at the base of said tongue in substantially opposite directions substantial 100 distances from said tongue, thence doubled 105 inwardly close to said outwardly extending portions to form hooks, the ends of said wire forming said hooks being thence bent into parallel sections extending from the base of said tongue longitudinally thereof and substantially parallel therewith to form a shank, the ends of the wires forming said shank being thence bent divergently relatively to each other substantially in a plane containing the longitudinal median lines of 110 wires forming said shank, the ends of said divergently extending portions being bent to form means for securing said cleat to a support, each of said means being disposed oppositely to one of said hooks, said means 115 being disposed at different distances from their respective hooks.

In testimony whereof I have hereunto set my hand in presence of two subscribing witnesses.

WARREN F. FRASER.
